UNITED STATES PATENT OFFICE.

AUGUST H. FURSTNOW, OF FOND DU LAC, WISCONSIN.

COMBINED NAME-PLATE AND HAT-HOOK.

SPECIFICATION forming part of Letters Patent No. 549,191, dated November 5, 1895.

Application filed March 8, 1895. Serial No. 541,014. (No model.)

To all whom it may concern:

Be it known that I, AUGUST H. FURSTNOW, a citizen of the United States, and a resident of Fond du Lac, in the county of Fond du Lac and State of Wisconsin, have invented 5 certain new and useful Improvements in a Combined Name-Plate and Hat-Hook; and I do hereby declare that the following is a full, clear, and exact description thereof.

10 My invention relates to a combined name-plate and hat-hook; and it consists in certain peculiarities of construction and combination of parts, as will be fully set forth hereinafter, and subsequently claimed.

15 In the drawings, Figure 1 is a view of a portion of a hat with my device applied thereto. Fig. 2 is an inside view of a portion of the sweat-leather of a hat, showing the attaching portions of my device. Fig. 3 is a 20 perspective rear view of my device detached, and Fig. 4 is a perspective view of a hat with my device in place therein and in position to be used as a hook.

25 Referring to the drawings, A represents a hat, and B the sweat-leather thereof.

C represents the name-plate, forming a part of my device, on which the name of the owner is designed to be engraved. On the back of this plate C are two transverse sleeves a a for 30 the reception of the arms b b, which are movable therein, and which, with the suspension-bar c, are formed of a single strip of wire, the free ends of said arms being upset, as shown at d d, to prevent detachment after said arms 35 have been inserted through the sleeves a a.

D is a sharp-pointed prong, rigidly attached to the rear of the plate C, adjacent to one end thereof, and projecting beyond said end.

E is another prong, pivotally secured, as 40 shown at e, to a lug f on the rear of said plate C, adjacent to the other end thereof, and F is a third prong, coinciding in form to the prong E and pivotally secured thereto, as shown at g.

45 The operation of my device will be readily understood from the foregoing description of

its construction, taken in connection with the accompanying drawings. In adjusting the device to the sweat-leather of a hat the latter is raised and the rigid prong D first inserted 50 through the same, and then the prongs E F are turned to a right angle to said sweat-band and pushed through it, and then spread out, as indicated in Fig. 2. When the hat is to be worn, the hook part b b c is pushed inward 55 toward the crown of the hat until the bar c is close to the plate C, as shown in Fig. 1, and when the hat is to be hung up the bar c is pulled out until the upset ends d d of the arms b b are against the adjacent ends of the 60 sleeves a a, with the bar c beyond the brim of the hat, as shown in Fig. 4. Thus it will be seen that I have devised a very neat and attractive device and combined with the name-plate a most convenient means for suspending 65 the hat when not in use.

By means of my device a hat can be suspended from a tack or even a heavy pin, and thus (as nearly every man carries pins in his pocket or about his clothing) a hat provided 70 with my device may be quickly, safely, and conveniently suspended in places where there are no regular hat-racks or hooks.

Having thus described my invention, what I claim as new, and desire to secure by Letters 75 Patent, is—

The herein described article of manufacture, comprising a name plate for hats, with attaching prongs and transverse sleeves secured to the rear side thereof, and a suspension device having arms in movable engagement with said sleeves, substantially as set forth.

In testimony that I claim the foregoing I have hereunto set my hand, at Fond du Lac, 85 in the county of Fond du Lac and State of Wisconsin, in the presence of two witnesses.

AUGUST H. FURSTNOW.

Witnesses:

MARK CRAIN,
H. W. NEWTON.
